F. G. GRUEN

CLASP

Filed Oct. 8, 1920

Inventor

Frederick G. Gruen
By Walter Murray

Attorney

UNITED STATES PATENT OFFICE.

FREDERICK G. GRUEN, OF CINCINNATI, OHIO, ASSIGNOR TO THE GRUEN WATCH COMPANY, OF CINCINNATI, OHIO, A CORPORATION OF OHIO.

CLASP.

Application filed October 8, 1920. Serial No. 415,600.

To all whom it may concern:

Be it known that I, FREDERICK G. GRUEN, a citizen of the United States of America, and resident of Cincinnati, in the county 5 of Hamilton and State of Ohio, have invented a new and useful Improvement in a Clasp, of which the following is a specification.

An object of my invention is to provide a 10 clasp that is especially adaptable to wrist bands such as are used on wrist watches, etc.

Another object is to provide a clasp that 15 will be ornamental as well as useful.

Another object is to provide a neat, simple and relatively thin clasp that will be light in weight and that will give efficient 20 service.

These and other objects are attained by 25 the means described herein and disclosed in the accompanying drawing in which:

Fig. 1, is a plan view of a clasp embodying 30 my invention, mounted upon a wrist watch band.

Fig. 2, is an enlarged sectional view on 35 line 2—2 of Fig. 1.

Fig. 3, is an enlarged perspective view of 40 the rear of the plate forming a detail of my invention.

Fig. 4, is an enlarged fragmental perspective view of the rear of the base forming 45 a detail of my invention.

The plate A has a lug a extending therefrom, the lug having a head a' formed 50 above the parallel longitudinal notches a² and a³ formed in the sides of the lug. The notches form seats for a purpose that will be explained hereafter.

The base B comprises a frame b between 55 the sides b' and b² of which extends cross bar b³ having a central slot b⁴. A spring b⁵ having arms b⁶ and b⁷ is mounted on the cross bar, and is retained thereon by the lug b⁸ extending from side b² and securing the 60 loop b⁹ formed on the spring, to the frame b.

The spring arms b⁶ and b⁷ have their ends b¹⁰ and b¹¹ respectively embedded in the side b' of the frame. The arms are arched adjacent their ends, the arm sections, between 65 the arched sections b¹² and b¹³ and the eye b⁹,

being parallel and extending over the slot b⁴ in the bar b³. The arms are spaced from one another a distance slightly less than the thickness of the lug a between the notches a² and a³ therein. 55

The band C is attached to the plate and the base and extends around the wearer's arm or wrist.

The operation of my device is as follows:

The plate A is placed over the base B, the lug a extending into the slot b⁴ in the base. By exerting pressure upon the plate A, the head a' on the lug is moved upon the arms b⁶ and b⁷ of spring b⁵, pushing such arms apart and causing the head to pass beyond 60 said arms. As soon as the head has passed the arms, the spring arms tend to resume their normal or unstrained position, whereby the arms seat in the notches a² and a³ on the lug and secure the lug between them, consequently holding the plate upon the base. The plate and base are separated by moving the head of the lug back between the arms and thru the slot b⁴. This is readily accomplished by inserting the finger nail between 65 the plate and base.

What I claim is:—

1. In a clasp the combination with a base 70 adapted to be secured upon a wrist band and comprising a frame, a slotted cross-bar on the frame, spring arms mounted on the frame adjacent the slot in the cross-bar, of a plate adapted to be secured upon a wrist band, and a lug extending from the plate, the lug being adapted to extend thru the 75 slot in the cross-bar and to be secured between the spring arms. 80

2. In a clasp the combination with a base 85 comprising a frame adapted to be secured upon a wrist band, a slotted cross-bar on the frame, spring arms mounted on the base and extending over the cross-bar adjacent the slot therein, of a plate adapted to be secured to a wrist band, a lug on the plate, and a head on the lug, the head being adapted to 90 pass thru the slot and between the spring arms, whereby the lug will be yieldably retained in frictional contact with the spring arms. 95

3. A clasp comprising a base, a spring and 100

a lug plate, the base having sides connected by a slotted cross bar, the spring having arms with a connecting loop and with arches at their ends, the spring being mounted upon the base with its arms located upon opposite sides of the slot and with the loop engaging one of the sides of the base and its

ends engaging the other side of the base and the plate having a lug adapted to pass through the slot and to engage the arms. 10

In witness whereof, I have hereunto subscribed my name this 7th day of October, 1920.

FREDERICK G. GRUEN.
